Primary Examiner — Austin Murphy(74) *Attorney, Agent, or Firm* — Schwegman Lundberg & Woessner, P.A.(57) **CLAIM**

The ornamental design for a mouse, as shown and described.

DESCRIPTION

FIG. 1 is a perspective view of a mouse showing our new design;

FIG. 2 is a front elevational view thereof;

FIG. 3 is a rear elevational view thereof;

FIG. 4 is a left side elevational view thereof; (A right side elevational view is omitted since it appears symmetrically with a left side elevational view)

FIG. 5 is a top plan view thereof;

FIG. 6 is a bottom plan view thereof;

FIG. 7 is a VII-VII cross-sectional view with internal mechanism omitted therefrom; and,

FIG. 8 is a VIII-VIII cross-sectional view with internal mechanism omitted therefrom.

The features shown in broken lines depict environmental subject matter only and form no part of the claimed design.
